ADJUSTABLE HINGE MECHANISM

Henry E. Hubbs, Shelby, Ohio, assignor to The
Shelby Spring Hinge Co., Shelby, Ohio, a cor-
poration of Ohio

Application July 14, 1948, Serial No. 38,599

7 Claims. (Cl. 16—129)

1

The invention relates generally to hinges for swinging doors and more particularly to double acting checking floor hinges.

Such checking floor hinges ordinarily include a checking mechanism embedded in the floor with an upwardly projecting stud which is received in a socket in a hinge arm secured on the underside of the door at its hinge side. The door is installed after the checking mechanism has been embedded in the floor, and it is therefore necessary to provide some adjustment of the door relative to the hinge arm so that the door is in proper position when the hinge arm registers with the stud of the checking mechanism.

With wooden doors, some adjustment is had by planing off the edge of the door, but with glass and metal doors, this cannot be done, and a positive adjusting means must be provided. Also, conventional glass doors have an adjustment at the top hinge, and a corresponding adjustment at the floor hinge is necessary. Certain prior adjusting means for checking floor hinges for glass doors have constituted merely providing a hole in the hinge arm which receives a pin attached to the door, and a set screw is screwed into the inner end of the arm and engages the pin for adjusting the position of the door relative to the arm.

Such prior adjusting means have numerous disadvantages, because the vibration of the door in operation gradually loosens the set screw, destroying the adjustment of the door and allowing it to sag at its free edge. Moreover, the set screw does not hold the pin in fixed position unless the other end of the hinge arm is secured tightly to the door, with the result that the hinge arm is apt to drop out of the door when being installed, and the door has a tendency toward limited edgewise movement when in operation.

It is an object of the present invention to provide an improved adjustable hinge mechanism for double acting checking floor hinges which overcomes all of the difficulties of prior adjusting means.

Another object is to provide an improved adjustable hinge mechanism employing an adjusting screw which is adapted to remain in any adjusted position, regardless of vibration during operation of the door.

A further object is to provide an improved adjustable hinge mechanism which will maintain the door in adjusted position during operation without permitting any sagging of the free edge of the door.

Another object is to provide an improved ad-

2

justable hinge mechanism in which none of the parts can drop out of the bottom of the door while it is being installed.

A still further object is to provide an improved adjustable hinge mechanism having novel adjusting means which always holds the hinge arm and door in fixed adjusted position without permitting any edgewise movement of the door.

Finally, it is an object of the present invention to provide an improved adjustable hinge mechanism for a double acting checking floor hinge, which mechanism is compact and inexpensive to manufacture, which is adapted to be installed on standard checking floor hinges, and which is easily installed and adjusted without special tools.

These and other objects are accomplished by the parts, constructions, arrangements, and combinations which comprise the present invention, the nature of which is set forth in the following general statement, and a preferred embodiment of which is set forth in the following description and illustrated in the accompanying drawings, and which is particularly and distinctly pointed out and set forth in the appended claims forming part hereof.

In general terms, the adjustable hinge mechanism of the present invention preferably includes a hinge arm having an elongated slot for receiving a depending pin attached to the underside of the door, an angle bracket slidable endwise of the arm and having a hole receiving the pin and registering with said slot, there being a screw adjustably mounting the angle bracket on the arm, and friction washer means for holding the screw in adjusted position.

Referring to the drawing forming part hereof in which a preferred embodiment of the invention is shown by way of example:

Figure 1 is a front elevation of the bottom part of the glass door embodying the improved adjustable hinge arm, partly in section, as on line 1—1, Fig. 2;

Figure 2 is a bottom plan view thereof with the stud of the checking mechanism removed;

Figure 3 is a fragmentary plan sectional view as on line 3—3, Fig. 1; and

Figure 4 is a fragmentary cross sectional view as on line 4—4, Fig. 1.

Similar numerals refer to similar parts throughout the several views of the drawing.

The adjustable hinge arm construction is shown in the drawing as incorporated in a double acting checking floor hinge for a glass door, but it will be understood that it may be applied to other

doors such as metal doors, without departing from the scope of the invention.

The glass door shown may have a glass panel 5 which is preferably provided with a rounded edge 6 on its hinge side, and the panel is mounted in usual fashion in an upwardly open metal channel member 7 which is secured as by welding to a downturned channel member 8 extending along the bottom edge of the door. The glass panel 5 is set in the door by means of a usual binder or grouting material indicated at 9, and the inner edge of the channel 7 is preferably rounded as indicated at 10 to conform to the rounded edge 6 of the panel. Likewise, the exterior surface of the inner end wall 12 of the bottom channel 8 is similarly rounded.

The checking mechanism for the floor hinge is of conventional construction and is therefore not shown except the part which protrudes above the floor F, the checking mechanism being embedded in the floor so that its top plate is flush with the floor surface. A boss 13 projects above the floor from the checking mechanism and a tapered hinge stud 14 projects upwardly from the boss 13. The hinge arm is preferably a solid bar 15 which is mounted within the bottom channel 8, and which has a tapered socket 16 non-rotatably receiving the tapered stud 14 of the checking mechanism, so that as the door swings about the stud 14 as a pivot, the stud rotates axially against the yielding resistance of the checking mechanism.

The outer end of the hinge arm 15 is adjustably secured to the legs of the channel 8 for permitting lateral adjustment of the arm with respect to the door, so that the door can be aligned with its sill when installed. Such securing means preferably includes an adjusting bolt 17 threaded through the outer end 18 of the arm 15 and extending through enlarged holes 19 in the channel-legs, there being large washers 20 interposed between the channel legs and the head and nut of the adjusting bolt 17.

The novel means for providing edgewise adjustment of the door relative to the hinge arm preferably includes a cylindrical pin 21 secured in and depending from a bracket plate 22 which is attached, as by countersunk screws 23, to the underside of a mounting bar 24 secured to the top wall or web of channel 8. The bracket plate 22 preferably has a slot 25 registering with the open socket 16 to allow the upper end of stud 14 to protrude above the hinge arm 15 if necessary.

The pin 21 is received in an elongated slot 26 extending vertically through the inner end of the hinge arm and a reduced end 27 is provided on the pin 21 for receiving a washer 28 which is held on the reduced end by a cotter pin 29. As shown in Figs. 2 and 4, the washer 28 extends over the side-edges of the slot 26 so as to prevent the arm 15 from dropping off pin 21 before the arm is positioned over the stud 14 of the checking mechanism when the door is being installed.

The means for adjusting the pin 21 in the slot 26 so as to adjust the door edgewise of the arm 15 preferably includes an angle bar 30, the upper leg 31 of which is slideable longitudinally of the arm 15 in a recess 32 in the upper surface thereof. The leg 31 is provided with a circular hole 33 through which the pin 21 extends, and the outer vertical leg 34 of the angle bar has an adjusting screw 35 mounted therein. The adjusting screw is threaded into the end wall 36 of the hinge arm 15 and is rotatable in the leg 34 of the angle bar, so that by turning the screw 35, the angle bar is

moved longitudinally of the arm 15, which consequently moves the door edgewise relative to the arm.

Means for preventing the adjusting screw 35 from loosening or turning, due to vibration of the door in operation, preferably includes a split washer 37 interposed between the screw head and leg 34, and a friction washer 38 engirdling the screw in abutment with the inner surface of the leg 34. As shown, the end wall 12 of the bottom channel 8 is provided with a suitable aperture 40 aligned with the screw 35, to permit the insertion of a screw driver from the exterior of the door, when it is desired to turn the adjusting screw 35.

Accordingly, when the door is positioned with the socket 16 of the hinge arm wedge-fitting over the stud 14 of the checking mechanism, the door may be adjusted edgewise to or from the jamb 41 by turning the adjusting screw 35 to move the pin 21 longitudinally in the slot 26 in the hinge arm 15, the adjusting bolt 17 having been slightly loosened so that it can move in the holes 19. At any adjusted position, the screw 35 will stay put because of the washers 37 and 38, so that the door will remain in adjusted position in operation regardless of vibration, and will not sag at its outer edge, as it would tend to do if the adjusting screw 35 could work loose and allow the door to move edgewise of the sill.

Due to the fact that the angle adjusting bar 30 is always tightly engaged around the pin 21, there can be no play or edgewise movement of the door in any adjusted position, because the adjusting means does not rely on engagement of the screw 35 with the pin 21, in which case the pin could move between the screw 35 and the opposite end of the slot 26. The washer 28 holds the hinge arm 15 in position during the installing operation, so that the arm 15 cannot drop out accidentally before it is positioned on the stud 14.

Accordingly, the improved adjustable hinge mechanism overcomes all of the difficulties had with prior constructions, and provides an inexpensive and easily installed adjusting hinge mechanism, which is adapted for use with standard checking floor hinges without requiring special tools.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiment of the improved construction illustrated and described herein is by way of example, and the scope of the present invention is not limited to the exact details of construction.

Having now described the invention, the construction, the operation and use of a preferred embodiment thereof, and the advantageous new and useful results obtained thereby; the new and useful constructions, and reasonable mechanical equivalents thereof obvious to those skilled in the art, are set forth in the appended claims.

I claim:

1. In a checking floor hinge for a door, adjustable floor hinge mechanism including a pin depending from the bottom of the door, a hinge arm having an elongated slot receiving said pin, an adjusting bracket slidably mounted on said arm and having a hole fitting snugly around said pin and registering with said slot, a screw adjust-

ably connecting said arm and bracket for relative movement in either direction edgewise of the door, and friction washer means on said screw for holding the screw in adjusted position.

2. In a checking floor hinge for a door, adjustable floor hinge mechanism including a pin depending from the bottom of the door, a hinge arm having an elongated slot receiving said pin, an adjusting bracket slidably mounted on said arm and having a hole fitting snugly around said pin and registering with said slot, and a screw adjustably connecting said arm and bracket for relative movement in either direction edgewise of the door.

3. In a checking floor hinge mounted on the underside of a door and having a hinge arm extending edgewise of the door and detachably connected to a checking mechanism in the floor, said hinge arm having a slot elongated longitudinally of the arm, a pin secured to the bottom of said door and extending into said slot, an adjusting bracket movably mounted on said arm and snugly engirdling said pin, a screw adjustably connecting the arm and bracket for adjusting the bracket longitudinally of said arm in either direction, and friction washers on said screw for holding the screw in adjusted position.

4. In a checking floor hinge mounted on the underside of a door and having a hinge arm extending edgewise of the door and detachably connected to a checking mechanism in the floor, said hinge arm having a slot elongated longitudinally of the arm, a pin secured to the bottom of said door and extending into said slot, an adjusting bracket movably mounted on said arm and snugly engirdling said pin, and a screw adjustably connecting the arm and bracket for adjusting the bracket longitudinally of said arm in either direction.

5. In a checking floor hinge for a door, adjustable floor hinge mechanism including a pin on the bottom of the door, a hinge arm having an elongated slot receiving said pin, an adjusting bracket slidably mounted on said arm and having a hole

fitting snugly around said pin and registering with said slot, a screw adjustably connecting said arm and bracket for movement in opposite directions, and a washer on the end of said pin and overlapping said slot for supporting said hinge arm.

6. In a checking floor hinge mounted on the underside of a door and having a hinge arm extending edgewise of the door and detachably connected to a checking mechanism in the floor, said hinge arm having a slot elongated longitudinally of the arm, a pin secured to the bottom of said door and extending into said slot, an adjusting bracket movably mounted on said arm and snugly engirdling said pin, a screw adjustably connecting the arm and bracket for adjusting the bracket longitudinally of said arm in either direction, and a washer on the end of said pin and overlapping said slot for supporting said hinge arm.

7. In a checking floor hinge mounted on the underside of a door and having a hinge arm extending edgewise of the door and detachably connected to a checking mechanism in the floor, said hinge arm having a slot elongated longitudinally of the arm, a pin secured to the bottom of said door and extending into said slot, an angle bracket movably mounted on said arm and snugly engirdling said pin, a screw adjustably connecting said arm and angle bracket for adjusting the bracket longitudinally of the arm in either direction, and a washer frictionally engirdling said screw and abutting said angle bracket for holding said screw in adjusted position.

HENRY E. HUBBS.
